tion of America, New York, N. Y., a corpora-
tion of Delaware

Application December 24, 1936, Serial No. 117,658

4 Claims. (Cl. 250—20)

The present invention relates to signalling systems and, in particular, to circuit arrangements adapted for use in connection with the operation of electron and vacuum tubes of the general types 5 described in our U. S. Patent No. 1,903,569, issued on April 11, 1933, on which a reissue application Serial No. 16,108 has been filed on April 8, 1935. Still further and more particularly this invention relates to the use of primary and secondary elec- 10 tron streams and associated tube and circuit elements and operating potentials for producing systems having a high degree of detecting efficiency.

An object of our invention is to provide in a 15 single tube structure with coating tube and circuit elements, a demodulator of modulated high frequency and an amplifier of the modulation frequency.

Another object of our invention is to provide a 20 demodulating system wherein the modulation frequency is amplified while the modulated frequency is suppressed.

A still further object is to provide for the 25 simultaneous combination of effects produced by nonlinear response of two separate frequencies, while preventing mutual interaction between their sources.

Another object of our invention is to provide a 30 highly efficient detector, whose detecting efficiency is substantially unaffected by its output circuit.

A still further object of our invention is to combine the effects of an ordinary grid-potential-anode current characteristic of a triode with the 35 secondary emission characteristic of an electron multiplier to produce a new and more efficient demodulator.

A further object of our invention is to provide a 40 more sensitive detector by utilizing the threshold effect of secondary emission.

Still other and further objects will be apparent in the following description and in the appended claims.

Three figures are attached for better description. Fig. 1 shows a simple circuit arrangement 45 utilizing the tube and circuit of our invention;

Fig. 2 discloses curves where current is plotted against time in order to show the relationship between control grid potential and several of the 50 currents in the tube; and

Fig. 3 discloses a modification of the circuit of Fig. 1 where the circuit structure is particularly designed for the simultaneous detecting or mixing of two frequencies.

In Fig. 1, the reference character 1 indicates

the electron tube referred to above. The numbers 2 and 3 refer to the input terminals where the modulated high frequency potential is impressed. The transformer 4 is tuned substantially to the incoming frequency by the condenser 5. The high potential end of the transformer 4 is connected to the control grid 6 of the electron tube 1, while the low potential end of the transformer 4 is connected through the polarizing potential 7 to the filament electron 10 emitter 8, also an element in tube 1. A collector plate 9 is provided, and connected back to the emitter 8 through the source of potential 10. Another element in the tube 1 is the output plate 11, which is connected through the inductance 12, to the low frequency transformer 13, and the source of potential 14 back to the emitter 8. There is also provided the shielding element 15, which is similarly connected back to the emitter 8 through the source of potential 16. The collector plate 9 is treated or otherwise made to be productive of high secondary emission of electrons from impact of a primary stream of electrons. Such a primary stream is indicated at 17, and flows from the emitter 8 to the collector 20 plate 9. Due to the impact of the impinging electrons and the properties of the electrode 9, a greater number of charges are emitted than are received in view of the potentials applied. These 25 secondary charges flow to the output plate 11 as indicated by the reference character 18. The shield 15, its position in relation to the other electrodes, and its applied potential determine the paths of the charge streams 17 and 18. A more detailed description of the purpose and action 30 of this screening element 15 will be found in the Patent No. 1,903,569 referred to above.

It is assumed that proper operating potentials are applied to all the elements of the tube, including the source of potential 19 used for heating the emitter 8 to render it electron emissive. The potential 14 is made high enough so that secondary emission saturation from the collector plate 9 throughout the operating range desired is obtained. Fig. 2 is a plot of voltage between 40 the control grid 6 and the primary emitter 8, with respect to the two emission currents 17 and 18 previously mentioned. The curve indicated as I_{17} in Fig. 2 shows the magnitude of the charge stream flowing between the emitter 8 and the collector plate 9 as the potential on the grid 6 is varied. This curve is quite similar to such a curve for the normal and well known three element electron tube. If an operating point is chosen, such as shown by the dashed line 21, 55

where the value of the polarizing potential E_7 is shown, it may be observed that the characteristic I_{17} is very definitely curved. As is well known in the art, if a modulated signal be superimposed on the voltage E_7 , so that the instantaneous potential on the grid 6 is varying symmetrically about the potential E_7 , a non-symmetrical current variation is produced. The effect of this non-symmetrical current relationship is to produce, in addition to the applied high frequency, components corresponding to currents of the fundamental, and multiple, modulation frequencies. As it is the fundamental modulation frequency component that is generally desired in detection, it is obvious that this gives a means of detection. It is also well known in the art, that the greater the rate of change in curvature,

$$\frac{d^2I}{dE^2_{G-F}}$$

the more sensitive will be the detector. It is to obtain this higher degree of curvature that the tube and associated circuits of our invention function.

By our invention, we can obtain a greater rate of change of curvature as shown by the characteristic I_{18} . This is obtained in the following fashion: Assume zero potential on the collector plate 9, while the output plate 11 is maintained at a constant potential above the collector plate 9. Under these conditions no current 17 will flow, nor will there be any current 18 as there is no primary emission to dislodge the secondary charges. Now let the voltage 10 be gradually increased. The current 17 will begin to rise as more and more electrons are attractive to the surface of the collector plate 9. At first, however, these electrons have barely enough velocity to reach the plate, and so are incapable of dislodging any secondary emission. As the collector plate 9 potential 19 is raised, the primary emission gains in velocity and finally a few primary electrons acquire sufficient kinetic energy to dislodge secondary charges. These are drawn over to the output plate 11 and appear in Fig. 2 as the intersection of I_{18} and the abscissa. As the potential on the collector plate is still further increased more primary electrons reach the collector plate, and with a much higher velocity. This twofold effect, of greater numbers and greater velocities, serves to very rapidly increase the secondary emission from the collector plate 9, all of which is drawn over to the collector plate 11. As a result of this effect, the current 18 increases with extreme rapidity as the collector plate potential is raised and is shown by the curve I_{18} in Fig. 2. Using a fixed collector plate potential, exactly the same effect is produced by raising the grid 6 from a negative value which produces current cutoff toward a positive value as shown in Fig. 2. As a result, a very sharp break in the curve results, and extreme sensitivity is obtained, since the curvature of I_{18} is due to product of I_{17} multiplied by the variable ratio of secondary to primary emissions.

As the potential is further increased as described, a point is reached at which very little further increase in ratio of secondary emission to primary emission is obtained. The reason for this action is somewhat obscure, but a possible explanation has been given in a copending application Serial No. 15,712, filed April 10, 1935, and entitled "Electron tube circuits." After this limit has been reached, the current I_{18} is a constant multiple of I_{17} and equals the secondary emis-

sion ratio. As this may be at a point in the characteristic curve which is still curved, detection can take place as before described, except with the utilization of the secondary emission ratio to increase the sensitivity.

Thus there are two operating conditions for satisfactory detection. First, relying on the normal curvatures as described. Second, utilizing the sharp curvature produced at the threshold of secondary emission. With either of these conditions an added feature is possible in our invention. Reference is made to the choke coil inductance 12 in Fig. 1. This inductance is chosen to oppose the flow of currents at the frequencies impressed on the input terminals 2 and 3, while having little or no effect on the currents of modulation frequency for which the transformer 13 is effective. If such an impedance were included as shown in the plate circuit of a normal detecting system, the detecting efficiency would be greatly reduced due to the straightening out of the curve due to the well known dynamic action. In the system of our invention, the high frequency variations in current may be completed through the collector plate 9 and the battery 10 back to the emitter 8. As a result, only the modulation frequency variations need to flow from the collector plate 9 to the output plate 11 and through the other circuit elements 12, 13, 14 and 10. Therefore, any desired means, such as the choke 12 or by-pass condenser 20, may be used in the output circuit to prevent the high frequency input currents from being amplified and passed on to the modulation frequency channel, with a total disregard of their dynamic effects on the detection sensitivity.

It will be appreciated that this advantage is secured because the impedance of the path between the electrode 11 and emitter 8 has no effect upon the dynamic characteristics of the path between the emitter 8 and the electrode 9. Thus complete filtering may be obtained with no loss in performance, often an important consideration.

In Fig. 3 is shown a composite or dual detector wherein two frequencies may be heterodyned to produce sum or difference frequencies with a considerable degree of independence. The tube is indicated at 22, and contains an emitter 23, collector plate 24, output plate 25, a shield element 26, and two grids indicated at 27 and 28 for controlling the electron streams 29 and 30 respectively. The emitter is rendered thermionic emissive by heating by means of the source of potential 31. The input circuit to the first grid 27 is shown by the input terminals 32 and 33 which feeds the tuned circuit indicated at 34. The grid circuit of grid 27 is closed through the tuned circuit 34 and the polarizing potential 35 back to the emitter 23.

The terminals 36 and 37 serve as input points for the signal controlling the grid 28. The grid 28 circuit is closed through the tuned circuit 38 and the polarizing battery 39 back to the collector plate 24. It is important to note that this grid 28 circuit returns to the collector plate 24 and not to the emitter 23. The equivalent three element tube wherein the grid 28 exercises control comprises the collector plate 24 acting as the emitter, the control grid 28 and the output plate 25. It is true that the emission from the collector plate 24 is determined by the secondary emission ratio of the material on this plate 24, and the primary emission striking this collector plate, but otherwise the elements 24, 28 and 25 are a completely independent acting thermionic device analogous to the tube 21.

to the conventional three element thermionic tube. The grid 28 is biased negatively with reference to the emitter 24 by the source of potential 39.

5 The collector plate 24, energized by the source of potential 40, serves as an anode analogous to a conventional three element tube, the only unusual feature being that this collector plate has no impedance between itself and the low potential input, as would be necessary in any other system where the effects in this first tube are to be transferred to a second tube. As before explained in the above referred to Patent No. 1,903,569, the relay action of the secondary emission at the collector plate 24 is the sole means of combining these equivalent independent tubes.

10 The output plate 25 is connected through the output circuit 43 and the source of potential 41 to the emitter 23. It should be noted that if the current 30 is greater than the current 29, which is generally the case, current flows through the source of potential 40 in the reverse direction and thus absorbs rather than delivers power. This power is furnished by the source of potential 41.

20 The shield 26 is maintained at a desired potential by the source of potential 42.

25 One source of common coupling is possible even in these equivalent tubes coupled only by the electron streams at the collector plate 24. This occurs as follows. When controlled by a variable voltage on the grid 27, the current 28 and consequently the current 30, will vary likewise. There is a capacity effect between the variable current 30 and the grid 28. As a result, the variable effect produced by the potentials on the grid 27, 30 may be found on the grid 28, and so be effective in the circuits connected with the input circuit 38. In order to avoid this effect, it is desirable to place the potential having the most stable frequency on the grid 28, rather than on the grid 27. As an example, suppose the circuit of Fig. 3 be used as a first detector in a superheterodyne. The local oscillator should be used to excite the grid 27, and the distant radio signal should be used to excite the grid 28. This is because the local oscillator can hardly effect the frequency of the distant and powerful station, and the reverse control is prevented by the one way action of the secondary emission relay at the collector plate 24.

30 For proper combination, it is desirable that both the equivalent tube 23, 27, 24, and the equivalent tube 24, 28, 25 be operated on a nonlinear characteristic as before noted. When this is done, the two applied frequencies will give sum and difference terms as the frequency of the output.

35 In case the two applied frequencies are high and close together, a low or intermediate frequency is obtained in the output, as well as much higher frequencies. The lower frequency is generally desired, and this operation is usually known as heterodyne detection. If one frequency applied is high, and the other low, the sum and difference frequencies are both usually desired as they are the so-called sidebands of a modulated transmission. Such a process is known as modulation, and is well and easily accomplished by the teachings of our invention.

40 In the operation of the system of Fig. 3, it is usually desirable to have the tuned circuits 34, 38 and 43 resonant at the desired frequencies and, of course, other networks may be used in place of the illustrated simple ones. If it is desired, a

series inductance can be connected between the electrode 25 and the tuned circuit 43 for suppression of certain frequency components as pointed out above in the description of Fig. 1.

Having described our invention, what we claim is:

1. A superheterodyne detector comprising means for supplying carrier wave energy, means for supplying signalling energy, means for producing a stream of primary electrons, means for controlling the magnitude of the produced stream of electrons in accordance with the carrier wave energy, means for producing a stream of secondary electrons in accordance with the number of the controlled primary electrons which exceed a predetermined velocity, an electrode for collecting secondary electrons, and grid control means energized by the signalling energy and interposed only in the produced stream of secondary electrons for controlling the number of electrons which reach the collector electrode. 15

2. A superheterodyne detector comprising means for supplying carrier wave energy, means for supplying signalling energy, means for producing a stream of primary electrons, means for controlling the magnitude of the produced stream of electrons in accordance with the carrier wave energy, means for producing a stream of secondary electrons in accordance with the number of the controlled primary electrons which exceed a predetermined velocity, means for collecting secondary electrons, and grid control means energized by the signalling energy and interposed only in the produced stream of secondary electrons for controlling the number of electrons reaching the collecting means. 25

3. A superheterodyne detector comprising means for supplying carrier wave energy, means for supplying signalling energy, means for producing a stream of primary electrons, means for controlling the magnitude of the produced stream of electrons in accordance with the carrier wave energy, means for producing a stream of secondary electrons in accordance with the number of the controlled primary electrons which exceed a predetermined velocity, means for collecting secondary electrons, grid control means energized by the signalling energy and interposed only in the produced stream of secondary electrons for controlling the number of electrons reaching the collecting means, and means for transferring the charges of the collected electrons to an output circuit. 40

4. A superheterodyne detector comprising means for supplying carrier wave energy, means for supplying signalling energy, means for producing a stream of primary electrons, means for controlling the magnitude of the produced stream of electrons in accordance with the carrier wave energy, means for producing a stream of secondary electrons in accordance with the number of the controlled primary electrons which exceed a predetermined velocity, means for collecting secondary electrons, grid control means energized by the signalling energy and interposed only in the produced stream of secondary electrons for controlling the number of electrons reaching the collecting means, means for transferring the charges of the collected electrons to an output circuit, and means for subsequently suppressing predetermined energy components of the transferred charges. 55
